UNITED STATES PATENT OFFICE.

JOHN W. NEWBERRY, OF ROCKVILLE CENTER, NEW YORK.

LIQUID-FUEL BURNER.

Application filed March 12, 1926. Serial No. 94,110.

My invention relates to liquid fuel burners and more particularly to heaters adapted to burn hydrocarbons. It has for its general object the improvement of 5 wickless burners intended for use with liquid fuels, and its especial objects are the provision of a simplified structure adapted to installation for domestic use and particularly the adaptation of such a burner for installation in the standard type of kitchen 10 range employing coal or other solid fuel.

With these objects in view and other features of advantage and utility hereinafter more specifically pointed out, my invention 15 consists in a burner having a plurality of nested tubular elements so spaced as to present continuous chambers therebetween. These elements may be cylindrical or other closed-curve form in horizontal section, 20 according to the accommodation of the particular location. They are foraminated to permit circulation of gaseous fuel or air therethrough, and mounted upon a base having troughs alternating with air chambers corresponding to the contour of the vertical 25 chambers. This base is preferably a casting having troughs for liquid fuel formed therein, and open channels therebetween with upwardly extending tapered bars projecting from the sides of said channels, exterior to the troughs. These bars are tapered and adapted to guide the tubular elements to their seats upon shoulders upon the inner faces of the troughs, and to maintain 30 such tubular elements in proper spaced-apart relation and in correspondence with like series of downwardly extending tapered bars projecting from a plurality of plate members adapted to receive the tops of the 35 tubular elements upon shouldered seats formed on such members. These plate members rest upon the tubular elements and assist in maintaining them in spaced relation. The bars projecting from the plates, 40 between adjacent elements, register with the upwardly extending bars, to which they correspond in number and position. The air chambers intermediate the fuel chambers are thus divided into a series of vertical channels. The vertical channels in the air chambers intermediate the fuel troughs are closed 45 at their tops by said plates.

The accompanying drawings illustrate the preferred structural embodiments of my invention, in which drawings Fig. 1 is an elevational end view of a burner mounted in

the ash-pit of a coal range from which the fire-grate has been removed, and extending upwardly into the fire-box, parts of the range being shown in sectional elevation. 60 Fig. 2 is a side view, the top plate shown in Fig. 6 being removed, and parts being broken away to show underlying structure. Fig. 3 is a vertical sectional view on the line 3—3 of Fig. 2 as viewed in the direction indicated by the arrows 3—3. Fig. 4 is a plan view partly in perspective and partly in section upon the broken line 4—4 as viewed in the direction indicated by the arrows 4—4. Fig. 5 is a fragmentary sectional view on the line 5—5 of Fig. 4 viewed as indicated by the arrows 5—5. Fig. 6 is a top plan view of the burner shown in Fig. 1. Fig. 7 is a perspective view of a standard kitchen range showing, as an alternative 75 location, a burner when mounted in the firebox upon its grate bars.

Like reference numerals indicate like parts throughout the several figures, in which 1 is the ash-pit of a range and 2 the fire-box 80 thereof, 3 the fire brick or like resistant material lining the fire-box adjacent the oven, and 4 a water-back. 5 are vertical screw-threaded supports resting upon the plates 6 for adjusting the height of the burner base 85 31 and levelling same. 7 is the outer tubular element of the burner, pierced with suitable apertures 34, permitting the volatilized fuel to escape and mix with air or other combustion supporting medium. 8, 9 and 10 are 90 the tubular elements nested within 7 and similarly apertured. The base 31 has the outer wall 11 of the trough 13. Upon the inner sides of the walls of the trough 13 are shoulders 12, upon which seat the tubular 95 elements 7 and 8. A second trough 15 is similarly provided with shoulders upon which seat the tubular elements 9 and 10. The upwardly extending bars 14 upon the base 31 serve to locate the tubular member 100 7. These bars taper upwardly and serve to guide the tubular member 7 into its seat upon the shoulder 12 and to maintain it in position in co-operation with the series of similar bars 16 projecting upwardly from the base between the troughs 13 and 15 and within the air chamber formed between the tubular elements 8 and 9. Similarly, the innermost series of bars 17 serve to locate and maintain in position the tubular element 10. 105 By the use of these locating and supporting bars it is possible to use for the material of

the tubular elements, comparatively thin sheet metal without danger of its deformation by warping under heat. The sheet metal, as hereinafter explained, is preferable because it will heat up more rapidly and initiate the air currents, affording proper draft to the burner. The tubular elements are maintained in their spaced-apart relation by bars extending downwardly therebetween in correspondence with bars upon the base. These bars, as in the case of the two-trough burner illustrated, consist of three sets. Each set is carried by a plate adapted to rest upon the tops of the tubular elements and to receive the upper edges of these elements in shoulders formed upon the plates. 19 is the plate seating over the trough 13 having the downwardly extending tapered bars 22 serving to locate the outer tubular element 7 and maintain it in position exteriorly thereof. 20 is the inner plate having the downwardly extending bars 23 registering vertically with the bars 16 upon the base and serving to space apart and support the tubular elements 8 and 9. 21 is the innermost plate supporting the depending bars 24 which extend to the inner wall of the trough 15 and rest thereupon and serve to locate and support the inner tubular element 10. The tubular elements as thus spaced apart intermediate the troughs afford an elliptical, vertical chamber, corresponding to the contour of the troughs, for the passage of air through the series of passageways formed between the registering bars of upwardly and downwardly projecting bars 16 and 23, respectively. The plate 20 closes this chamber at the top and the air passes therefrom into the adjacent spaces above the troughs 13 and 15 through the perforations in the walls of tubular elements 8 and 9. These elements are maintained spaced apart above the troughs by means of collars 27, 28 and 29 upon the bolts 25 which pass through the tubular elements 7, 8, 9 and 10 and are held by nuts 26. Oil is supplied to the troughs 13 and 15, which are shown as of elliptical form, by a feed pipe 30 having the connection 31 to the trough 13 and the connection 32 to the trough 15. Drainage connections 33 are provided between the two troughs. Air is also supplied to the inner face of the tubular element 10 by the central chamber beneath the plate 21, which is of slightly less diameter on its greater axis than the chamber, affording the channel 35. The annular plate 19 has a marginal flange 36 projecting beyond the exterior face of the member 10 to baffle the rising air current and project it horizontally. The apertured plates 36', 37, hinged at 38, seated on the plate 21, constitute an adjustable baffle for dampering the heat and giving it direction. When either plate occupies the position indicated in outline as 39 in Figure 1, the air currents

are thrown from the closed to the open side and projected as preferred, either against the water-back or oven side of the fire-box. It is to be noted that the sets of corresponding bars 14 and 22, 16-23, and the bars 22, 70 serve to steady the ascending air currents that rise therebetween against lateral deflection, and that the walls of the fire-box co-operate with the bars 22 in promoting this result; and that the bars function not only 75 as guides, spacers and supports for the tubular elements and to prevent buckling or distortion of the sheet metal, but also as heat-storage and distribution media.

The oil feed for the oil supply pipe 30 80 may be of any usual and approved type, and is not shown, as it will be readily understood, and is not a part of my present invention.

With the structure shown, the use of sheet 85 metal in lieu of thicker metal is possible, and by virtue of its limited mass, a quicker heating is attainable. Obviously, the burner so constructed is more compact, and correspondingly smaller; it is lighter and also is 90 cheaper to manufacture. By the location of the burner within a fire-box and next to the fire-brick or lining, a draft is established between the outer wall-element of the burner and the said lining. The blue-flame heat 95 thus applied directly to the fire-brick adjacent the oven serves to expedite the heating of the oven. Tests with a burner constructed as shown, placed in a coal range with three-fourths of an inch clearance between the 100 burner and the fire-brick, have resulted in higher oven temperatures (500° F.) than are attained by use of coal, and in reaching baking temperatures (250° to 350° F.) in from forty-five to sixty minutes.

Certain features herein shown are disclosed in my copending application Serial No. 40,478, filed June 20, 1925, and are not herein claimed. Among the improvements thereover which I desire more particularly 110 to point out herein is the feature of dispensing with the outer housing of the burner previously used, as therein shown, and the utilization of the fire-box walls themselves as such housing, thereby substituting radiant heat for indirect heating by convection.

Having thus described my invention, which, it will be understood, is not limited in its useful application to the form or location shown and described as preferential, but may be employed advantageously in a furnace or like heater as well as in a stove or range, as shown, I claim:

1. A liquid fuel burner comprising a plurality of sheet metal tubular elements adapted to nest together, a base common thereto, a plurality of upwardly projecting bars upon said base, adapted to extend between adjacent tubular elements and to space same apart, and a top member adapted to rest 125 130 135

- upon said tubular elements, and a plurality of downwardly projecting bars upon said top member adapted to extend between adjacent tubular elements and to assist in maintaining same in spaced relation.
2. In a range, a combustion chamber, a combustion-resisting lining therein adjacent the oven side thereof, a pit below said chamber, a liquid fuel burner having fuel troughs, and means for levelling same, mounted in said pit, a baffle plate on said burner and means for adjusting same to direct a part of the flame from the burner directly against said lining.
- 10 3. A liquid fuel burner comprising a plurality of nested, foraminated elements, a base common thereto, open fuel channels in said base, a pair of tubular elements extending upwardly from said base on either side of each fuel channel and forming a chamber over each channel, said chambers being open at their tops; a series of bars projecting upwardly from said base from the exterior walls of said fuel channels and adapted to position the tubular elements relatively to 25 said channels, said bars being spaced apart and dividing the space between adjacent walls of the fuel chambers into a series of vertical air chambers communicating at their lower ends through said base to atmosphere, 30 and annular plates closing said air chambers at their upper ends.
4. A liquid fuel burner comprising a plurality of pairs of nested, foraminated, tubular elements; a base common thereto and 35 adapted to seat said elements; spacing members between said tubular elements, whereby a combustion chamber is provided above each fuel channel, and an air chamber is provided intermediate adjacent combustion chambers; 40 and an annular plate above each air chamber and seated upon said tubular elements; and bars depending from each plate and projecting downwardly into each air chamber.

JOHN W. NEWBERRY.
